UNITED STATES PATENT OFFICE.

LESTER S. MACDONALD, OF BEVERLY, MASSACHUSETTS, ASSIGNOR TO UNITED SHOE MACHINERY CORPORATION, OF PATERSON, NEW JERSEY, A CORPORATION OF NEW JERSEY.

FINISHING MACHINE.

Application filed December 26, 1922. Serial No. 609,038.

This invention relates to finishing machines and is herein shown as embodied in a machine for waxing and burnishing the edges of heels of boots and shoes.

5 Finishing machines for heels usually employ a series of rotary tools each of which has a contour made to fit the particular shape or style of heel to be finished. The necessity for a large number of different 10 tools to take care of the many different heel shapes is a source of expense and has other disadvantages. Accordingly, it is an object of this invention to provide an improved tool which is adapted for finishing heels of 15 many different shapes and degrees of curvature.

In the illustrated machine, this object is obtained by providing a finishing tool made up of a series of work rubbing elements 20 arranged for relative adjustment and having their work rubbing surfaces arranged in adjacent relation. Preferably, the resultant surface of the finishing tool is transverse to a driven shaft, being supported at their ends 25 by the shaft and an annular member surrounding and attached to the shaft, by means of which rotary movement is imparted to the tool and the elements of the tool are adjustable, as by distortion of the 30 individual elements, in a direction parallel to the axis of the shaft. This adjustment of the elements of the tool may be effected by the use of one or more adjustable backing members which are preferably resilient. 35 The latter have movement parallel to the shaft to produce a curved contour and radially of the shaft to vary the character or location of the curvature. To impart a yielding quality to the burnishing surface, 40 the backing members are spring-pressed against the rubbing elements and the tool as a whole is also mounted to yield under pressure of the work.

Another object is to provide improved 45 means for heating the tool and for supplying it with wax in the desired quantity. As shown, the tool is enclosed, except where the work is presented, by a casing which is electrically heated and transmits heat to the 50 tool by radiation. Both the casing and the wax supplying mechanism have a pivotal mounting so that they can be swung to one side to allow access to the tool.

These and other objects, features and ad-

vantages of the invention will appear from 55 a consideration of the detail specification with the accompanying drawings in which,

Fig. 1 is a perspective view of the operative parts of the machine, partly broken away and in section. 60

Fig. 2 is a perspective view of the rear side of the heated casing and the wax supplying mechanism.

Fig. 3 is a longitudinal vertical section. 65

Fig. 4 is a horizontal section of a portion of the machine.

Fig. 5 is a front elevation, partly broken away, of the burnishing tool.

Fig. 6 is a front view of the machine. 70

Fig. 7 is a detail perspective view of one of the spiral burnishing elements; and

Fig. 8 is a perspective view of the outer end of one of the spiral burnishing elements.

The burnishing tool of this invention is mounted at the end of a central, driven shaft 75 10 journaled in bearings in the frame. Fixed at the end of the shaft between two spaced collars 14 is a sleeve 12 having around its periphery a series of radially extending kerfs each adapted to receive the inwardly bent end of an elongated, flat, spiral rubbing element 16. The corners of the outer edges of the elements are relieved, as shown in Fig. 8, and their convolutions are received one within the other and collectively form a disk-like burnishing surface which is substantially continuous and at right angles to the shaft. The outer end of each element is bent laterally as indicated at 18 in Fig. 8 and again bent at right angles 80 to form a tongue 20 arranged to enter a groove 22 in a ring 24 which rotates with the shaft. The tongues 20 are held within the groove by lugs 28 extending laterally 85 from a ring 26 enclosing the ring 24, each lug overlying one of the rubbing elements adjacent to the bent portion 18. The ring 24 has projections 30 (Fig. 4) extending towards the shaft and secured by screw bolts 32 to arms 34 radiating from a central member or hub 36 splined to the shaft 10 by a key 38. In the illustrated machine, there are three projections 30 and three corresponding arms 34 which form driving 90 connections between the shaft and the outer ends of the rubbing elements. At the rear of the hub 36 is a coil spring 40 (Fig. 3) 95 arranged to thrust the hub forward and

100

105

keep it pressed against a stop collar 42 fixed to the shaft.

The burnishing surface is normally flat but can be changed to any desired contour by relative adjustment of the component parts as by means of a series of backing members herein shown as substantially egg-shaped springs 44 arranged to contact with the inner edges of the burnishing elements intermediate of their points of support and displace portions of them parallel to the axis of the tool thereby distorting the individual elements. Each spring 44 is like a helix which is tapered at each end to a reduced but definite diameter. In the openings thus formed at the ends of the springs 44 are received the forks 46 (Fig. 5) of members 48 which are loosely pivoted by means of shoulered pins 50 (Fig. 4) to the inwardly extending flange of a ring 52 slidably held within the ring 24. The flange of the ring 52 is arranged to slide parallel to the shaft 10 on screw bolts 54 fixed to the projections 30, there being coil springs surrounding the bolts and normally holding the ring 52 in a forward position. The backing members 44 are arranged to be displaced laterally at their central portions in two directions, first in a direction parallel to the shaft and second in a direction radially of the shaft. These movements are produced by arched members 68 fitting the backing members and carrying a stem 60 slidable in a sleeve 62 of a bell-crank member pivoted at 64. A spring 66 surrounds each stem 60 and impels to its backing member a yielding quality which is required in order that the burnishing surface may search out and find the minor irregularities in the work. The forward movement of the backing members under the influence of the springs 66 is limited by pins 68 fixed to the stems and passing through slots in the sleeves of the bell-crank members. The central portions of the backing members are moved radially by means of sector gears 70 on the bell-crank members engaged by racks 72 on the end of a sleeve 74 (Fig. 3) which is slidable on the shaft 10 against the tension of the spring 40 hereinbefore referred to.

The pivot pins 64 of the bell-crank members are mounted in pairs of lugs 76 projecting radially from a sleeve 78 splined by means of a key 80 to the sleeve 74. The sleeve 78 has a peripheral groove 82 receiving at opposite sides rolls on the lower end of a lever arm 84 (Figs. 1 and 3) loose on a shaft 86 which is fixed in position on the frame. The lever arm 84 is coupled to a hand lever 88 having a spring-pressed pawl 90 arranged to engage with the teeth of a rack 92 fixed to an adjusting lever 94. The adjusting lever 94 has a hub which is loose on the fixed shaft 86. One end of a spring 98 is received back of a lug 96 (Fig. 6) on

the adjusting lever and its other end 100 is received in one of a series of notches formed back of the projections 102 on a casing 104. The casing is actuated by a handle 106 which is hollow and houses a spring-pressed pawl 108 (Fig. 1) arranged to engage the teeth of a ratchet 110 which is fixed to the shaft 86. By releasing the pawl and turning the handle, the tension of the spring 98 may be adjusted to the desired degree to take the thrust of the work against the tool. The spring 98 normally holds the adjusting lever 94 with its lower arm 112 against a fixed stop 114 (Figs. 1 and 3) in the frame, but these two parts can separate if the pressure of the work exceeds a certain amount.

Extending upwardly from the roll-carrying lever arm 84 is an arm 116 connected by a link 118 to an arm 120 on a hub 122 journaled in the frame and having a connected adjusting arm 124. The arm 124 has a rack member 126 engaged by a spring-pressed pawl 128 carried by a hand lever 130 which is fixed to a shaft 132. The shaft is loose within the hub 122 and has fixed to it an arm 134 which extends downwardly and has at its lower forked end a pair of rolls received in a groove 136 of the sleeve 74 above referred to. By depressing the pawl 128 from the rack teeth, the hand lever 130 may be independently actuated to slide the sleeve 74 and thereby move the racks 72 (Fig. 3) and the sector gears 70 to throw the central portions of the backing members 44 towards or from the shaft 10. Movement of the other hand lever 88 effects the movements of both sleeves as follows:—By depressing the pawl 90 the hand lever 88 may be actuated to rock the lever arm 84 and slide the outer sleeve 78 in a direction parallel to the shaft. Equal sliding movement is imparted to the inner sleeve 74 through the link 118, arm 120, hub 122, lever 124, rack 126, hand lever 130, rock-shaft 132 and arm 134. Movement of both sleeves, through the backing members, displaces the rubbing elements and forms a convexity in the tool surface. Having thus actuated the lever 88 to displace the convolutions in a direction parallel to the shaft, the character or location of the curvature thus produced can be adjusted by independent movement of the hand lever 130 which varies the radial positions of the backing members.

The resulting contour of the work rubbing surface of the tool thus produced is substantially uniform around its whole periphery, as illustrated in Fig. 4, because of the symmetrical arrangement of the various backing members around the axis of the shaft and the further fact that edgewise distortion of the individual rubbing elements 16 within the arc between adjacent backing members is inherently resisted by the edge-wise position of the elements 16.

- Surrounding the tool, except at that portion where the work is presented, is a cap-shaped casing 138 (Figs. 1 and 3) having a plurality of hollow bosses receiving electric heating units 140. The inner surface of the casing 138 is corrugated (Fig. 2) in order to radiate more heat to the working surface of the tool. A wax receptacle 142 is carried by the heated casing and rotatably receives the lower part of a wax transferring disk or wheel 144. The rotation of the disk in the liquid lifts a film of wax from the receptacle and the wax is scraped from the disk by a pair of forks 146 formed on a member which has a channel or groove 148 leading through an opening in the casing to the central part of the tool. The wax being supplied to the center of the tool spreads radially under the action of centrifugal force. To prevent the wax from being thrown off from the tool, the latter is rotated in the direction (Fig. 6) in which the convolutions of the spiral members open so that the effect of centrifugal force is largely neutralized. The direction of rotation is indicated in Fig. 6 as counterclockwise and is such that the rubbing elements rub the heel in the direction of the toplift.
- The wax transferring wheel is driven by a stub shaft 150 journaled in an arm 152 pivotally mounted on a stub shaft 154. The amount of wax taken by the tool from the disk is regulated by adjusting the degree of projection of the disk between the forks 146, and this is accomplished by an adjusting bolt 156 which passes through a curved slot in the arm 152. The wheel is driven from the stub shaft 154 by pulleys and a round belt 158. The stub shaft 154 has a toothed clutch member 160 at its rear end engaging a similar toothed clutch member 162 on the forward end of a shaft 164 journaled in the frame. The toothed connection allows the sections of the shaft to be separated. All of the parts including the wax transferring mechanism and the heated casing are mounted on an arm 166 pivoted on a rod 168 at one side of the tool and swing to one side to afford access to the tool. The clutch members are detachably held in engaged position by a bolt 172 pivoted between lugs 170 on the frame and having a wing nut 174 arranged to engage the forked free end of the arm 166.
- A tread rest 176 (Figs. 2, 4 and 6) for the heel of the shoe is adjustably mounted on the arm 166 and can be held in place by the hand nut 178. A side rest 180 (Figs. 2 and 6) is also mounted on the arm 166 and can be held in adjusted position by the hand nut 182 (Fig. 6). The shaft 164 has at its rear end a gear 184 (Fig. 1) driven by a worm 186 on the drive shaft 188. At one end of the drive shaft 188 is a bevel gear 190 meshing with a bevel gear 192 on the driven shaft 10 and this causes continuous rotary movement of the tool.
- In operation, the heel to be treated is presented to the working face of the tool. By manipulation of the hand lever 88 the backing members are moved parallel to the tool shaft to cause the tool to assume a curved contour. The character and location of this curvature can then be further regulated to fit the heel by independent operation of the lever 130. The heel is pressed rearwardly against the tool and turned as is usual in such machines to present all portions of its surface to the tool. The local yield is furnished by the spring in the backing members and in the springs that back them up. The yield to the tool as a whole is furnished by the spring 98 which opposes the thrust of the work.
- Having described my invention, what I claim as new and desire to secure by Letters Patent of the United States is:
1. In a machine of the character described, a finishing tool comprising a rotary driven member, a flexible rubbing element, curved outwardly from the axis of said driven member in the form of a spiral of Archimedes, and means for connecting only the ends of said element to the driven member arranged to allow variations of the contour of said element.
  2. In a machine of the character described, a finishing tool comprising a rotary driven member, a rubbing element extending from said driven member in the form of a spiral, mechanism for supplying wax to the element near the axis of rotation, and means for rotating said element in the direction that the convolutions of the spiral open to modify the effect of centrifugal force in spreading the wax.
  3. In a machine of the character described, a finishing tool comprising a central driven member and a plurality of flexible rubbing elements projecting from said central member in the form of spirals and having their convolutions one inside the other.
  4. In a machine of the character described, a rotatable shoe finishing tool comprising a central driven member, a driven supporting member spaced radially therefrom, and a plurality of rubbing elements having their working surfaces arranged closely adjacent to one another and extending from the central driven member to the periphery of the tool, said rubbing elements being supported at their ends by said members.
  5. In a machine of the character described, a shoe finishing tool comprising a driven shaft, an annular supporting member attached to and surrounding said shaft, and closely related flexible rubbing elements forming a substantially continuous disk-like work treating surface at substantially right angles to the shaft at the end thereof attached

to said member for rotation with the shaft.

6. In a machine of the character described, a finishing tool comprising a shaft, and work rubbing elements forming a working surface extending transversely of the shaft, and means for varying the contour of said working surface.

7. In a machine of the character described, a finishing tool comprising a shaft, work rubbing elements projecting from said shaft and forming a surface transverse to the shaft, and means for moving portions of said elements in a direction parallel to the shaft to make a curved rubbing surface.

15 8. In a machine of the character described, a finishing tool comprising a driven shaft, rubbing elements projecting from said shaft and forming a working surface normally in a plane at substantially right angles to the shaft, means for forcing portions of said elements in a direction parallel to the shaft to make a curved rubbing surface, and means for varying the distance from the shaft at which said first means acts.

25 9. In a machine of the character described, a finishing tool comprising a shaft, rubbing elements secured to the shaft and forming a disk-like rubbing surface; and means for forcing portions of said elements in a direction parallel to the shaft to vary the contour of said surface, said means being yieldably pressed against the rubbing elements to enable the latter to yield upon pressure due to minor irregularities in the work.

35 10. In a machine for finishing the parts of boots and shoes, a rotary finishing tool comprising a shaft, a series of rubbing elements projecting from said shaft and arranged to form a work rubbing surface, a backing member arranged to contact with the rubbing elements on the side opposite the work rubbing surface, and means for changing the effect of said backing member to vary the contour of said work rubbing surface.

45 11. In a machine of the character described, a rotary finishing tool comprising a shaft, a series of rubbing elements projecting from said shaft and arranged to form a work rubbing surface, a plurality of backing members arranged to contact with the rubbing elements on the side opposite the work rubbing surface, and means for moving said backing members to vary the contour of said work rubbing surface.

55 12. In a machine of the character described, a rotary finishing tool comprising a shaft, a series of rubbing elements projecting from said shaft and arranged to form a work rubbing surface, a plurality of backing members arranged to contact with the rubbing elements on the side opposite the work treating surface, means for moving said backing members parallel to the shaft to produce a curved contour for said work treating surface, and means for moving said

backing members toward or away from the shaft to vary the character of said curvature.

13. In a machine of the character described, a rotary finishing tool comprising a shaft, spiral work rubbing elements projecting from said shaft, the adjacent convolutions of the spiral elements being substantially in contact and arranged to shift in a direction parallel to the shaft, and means engaging one side of said rubbing elements for causing the opposite side to form a curved working surface.

10 14. In a machine of the character described, a rotary finishing tool comprising a shaft, a member supported for rotation with the shaft and having an adjustable work rubbing surface, a backing member, and means for moving said member to vary the contour of said work rubbing surface.

15 15. In a machine of the character described, a finishing tool comprising a shaft, an adjustable member supported for rotation with the shaft, and provided with a work rubbing surface, a backing member, means for moving said member to vary the contour of said work rubbing surface, and a spring between the backing member and the means for moving the adjustable member to impart a yielding quality to the work rubbing surface.

20 16. In a machine of the character described, a finishing tool comprising a shaft, a member having an adjustable work rubbing surface, said member being supported for rotation with the shaft, backing members, a sleeve slidable on the shaft and having connections constructed and arranged to move said backing members toward or from the shaft, and a second sleeve mounted for sliding movement with respect to the shaft and constructed and arranged to move said backing members parallel to the shaft.

105 17. In a machine of the character described, a rotary finishing tool comprising a shaft, a member having an adjustable work rubbing surface extending transversely of the shaft, and egg-shaped springs associated with said member and movably mounted to vary the contour of said work rubbing surface.

110 18. In a machine of the character described, a rotary finishing tool comprising a shaft, a member having adjustable work rubbing surface, yieldable backing members connected at their ends to the tool and means for moving the intermediate portions of said members transversely of their length to vary the contour of said work rubbing surface.

115 19. In a machine of the character described, a finishing tool comprising a shaft, a member at the end of the shaft having radial kerfs, rubbing elements having their ends in said kerfs, an outer ring driven by

said shaft, and connections between said ring and the outer ends of said elements.

20. In a machine of the character described, a finishing tool comprising a shaft, an inner member and an outer member spaced at a greater distance from the shaft, said members being driven by said shaft, and a rubbing element attached at its ends to said members. 70

10 21. In a machine of the character described, a finishing tool comprising a shaft, an outer support driven by the shaft and spaced therefrom, and a spiral rubbing element operatively connected to the shaft and the outer support. 75

15 22. In apparatus of the character described, a finishing tool, means for actuating the tool, a casing enclosing the tool, and means for heating the casing, said casing being corrugated on the inside to increase its heat radiating capacity on the side towards the tool. 80

20 23. In apparatus of the character described, a finishing tool, means for actuating the tool, a casing overlying the working face of the tool, means for heating the casing to heat the tool by radiation, and a pivotal mounting for said casing to afford access to said tool. 85

25 24. In apparatus of the character described, a finishing tool, a receptacle for wax, a disk rotatable in said receptacle to lift a film of wax, and a scraper in contact with said disk to remove wax therefrom and provided with a groove to convey it to the finishing tool. 90

30 25. In apparatus of the character described, a finishing tool, a receptacle for wax, a disk rotatable in said receptacle to lift a film of wax, and a forked member straddling said disk and having a groove to convey wax to the tool. 95

35 26. In a machine of the character described, a finishing tool, a receptacle for wax, a disk rotatable in said receptacle to lift a film of wax, means for removing the wax from the disk and conveying it to the tool, and means for adjusting the disk relatively to the removing means to regulate the quantity of wax conveyed to the tool. 100

40 27. In apparatus of the character described, a finishing tool, a receptacle for wax, a disk rotatable in said receptacle to lift a film of wax, a pivoted arm rotatably supporting the disk, means for adjusting the arm to regulate the supply of wax, and means for conducting the wax to the tool. 105

45 28. In apparatus of the character described, a finishing tool, means for actuating the tool, mechanism for supplying wax to the tool, and an arm carrying said wax supplying means and having a pivotal mounting to afford access to said tool. 110

50 29. In apparatus of the character described, a finishing tool, an arm pivoted at one side of the tool, mechanism mounted on the arm for supplying the tool with wax, and a sectional shaft for actuating said wax supplying mechanism, one section of the shaft being mounted on the arm and having a detachable clutch connection with the other section. 115

30. In apparatus of the character described, a finishing tool, an arm mechanism mounted on the arm for supplying the tool with wax, a heated casing mounted on the arm and overlying the tool to heat the latter, and a pivotal mounting for the arm to enable the casing and wax supplying mechanism to be swung away from the tool. 120

31. In apparatus of the class described, a shaft, a finishing tool having a burnishing surface extending transversely of the shaft, mechanism for conducting wax to the tool near its axis of rotation, and means for rotating the shaft and tool to spread the wax over the burnishing surface. 125

32. In a machine for finishing the parts of boots and shoes, a finishing tool made up of a series of work rubbing elements capable of relative adjustment and supported for rotation with their work rubbing surfaces in adjacent relation arranged to form an operating surface transverse to the axis of rotation, and an adjustable backing member constructed and arranged to coact with said work rubbing elements to determine and vary the contour of the resultant work rubbing surface. 130

33. In a machine for finishing the parts of boots and shoes, a movable driven member, a series of work rubbing elements capable of relative adjustment and operatively connected to said driven member for movement therewith, said elements having work rubbing surfaces arranged in adjacent relation, and an adjustable backing member constructed and arranged to coact with the inner edges of said work rubbing elements to determine and vary the contour of their combined outer work rubbing surfaces. 135

34. In a machine for finishing the parts of boots and shoes, a finishing tool made up of a series of work rubbing elements capable of relative adjustment and supported for movement with their work rubbing surfaces in adjacent relation, and a resilient backing member constructed and arranged to coact with said work rubbing elements to determine and vary the contour of their combined work rubbing surfaces. 140

35. In a machine for finishing the parts of boots and shoes, a finishing tool made up of a series of work rubbing elements arranged for relative adjustment and supported for movement with their work rubbing surfaces in adjacent relation, and a backing member adapted to be placed in contact with the inner edges of the individual elements so as relatively to displace said elements and 145

control the contour of the combined surface of the elements.

36. In a machine for finishing the parts of boots and shoes, a finishing tool made up of 5 a series of elongated work rubbing elements arranged for relative adjustment, means for supporting each of the ends of the various elements with the elements arranged in adjacent relation to form a work rubbing surface 10 whose contour is adjustable, and a backing member constructed and arranged to coact variably with said work rubbing elements intermediate between their points of support to distort the combined work rubbing 15 surface of the elements, thereby to produce a desired contour.

37. In a machine for finishing the parts of boots and shoes, a finishing tool comprising a shaft and a series of work rubbing elements 20 arranged for relative adjustment in a direction parallel to said shaft, said elements being operatively connected to said shaft for movement therewith and having their work rubbing surfaces arranged in adjacent relation 25 to form a combined work rubbing surface of which the contour may be varied by

the relative adjustment of the various rubbing elements.

38. In a machine for finishing the parts of boots and shoes, a finishing tool made up of 30 a series of work rubbing element arranged for relative adjustment and supported for movement with their work rubbing surfaces in adjacent relation, said elements being capable of individual distortion to the end that the resultant contour of the work rubbing surface formed by the adjacent surfaces of the component members may be varied. 35

39. In a machine for finishing the parts of boots and shoes, a finishing tool made up of 40 a series of work rubbing elements arranged for relative adjustment and supported for movement with their work rubbing surfaces in adjacent relation, and means coacting 45 with said elements to distort the individual elements to form a work rubbing surface whose contour is substantially uniform around its whole periphery.

In testimony whereof I have signed my name to this specification.

LESTER S. MACDONALD.

CERTIFICATE OF CORRECTION.

Patent No. 1,644,931.

Granted October 11, 1927, to

LESTER S. MACDONALD.

It is hereby certified that error appears in the printed specification of the above numbered patent requiring correction as follows: Page 1, lines 24, 25 and 26, strike out the words "being supported at their ends by the shaft and an annular member surrounding and attached to the shaft, "; same page, line 34, after the word and period "resilient." insert the words "As shown, the rubbing elements project from a rotary driven shaft, being supported at their ends by the shaft and an annular member surrounding and attached to the shaft, and the backing members engage the rear edges of the elements and cause the surface formed by the front edges of the elements to assume a contour dependent upon the position of the backing members. "; and that the said Letters Patent should be read with these corrections therein that the same may conform to the record of the case in the Patent Office.

Signed and sealed this 20th day of December, A. D. 1927.

Seal.

M. J. Moore,
Acting Commissioner of Patents.
